LOCKING DEVICE FOR THE SLIDING MEMBERS OF EXTENSIBLE FRAMES

Daniel A. Eberhardt, St. Louis, Mo.

Application December 11, 1947, Serial No. 791,084

3 Claims. (Cl. 287—58)

1

This invention relates to an improved clamp or lock for securing the extendible members of an extensible frame, such as a trouser creaser, in selected positions.

More specifically, the invention pertains to an improvement to the device disclosed in U. S. Patent No. 2,294,967 for Adjustable rod joint, issued September 8, 1942, to Daniel A. Eberhardt. The improvement resides, in part, in the provision of a clamp which while permitting the free movement of the members outwardly to an extended position, automatically operates to prevent their movement inwardly to a closed or contracted position. In the patented device the clamp or lock is operative, when in its clamping position, to secure the adjustable section of the frame against movement in both directions.

It is an object of the invention to provide a clamp or lock of the character described which is economical to manufacture, and which is efficient in service and lasting in wear.

Other objects and advantages will become apparent as the specification proceeds and a more comprehensive understanding of the invention will be afforded from the following detailed description when considered in conjunction with the accompanying drawing, in which

Fig. 1 is a plan view of a trouser creaser embodying the instant invention,

Fig. 2 is a perspective view of a clamp or locking device embodying the instant invention and showing the parts thereof,

Figs. 3 and 4 are plan views of the clamp shown in Fig. 2, showing, respectively, the relationship of the parts in clamping position and released position, and

Fig. 5 is a plan view of the clamp shown in Fig. 2, illustrating the same in modified form.

For the purpose of disclosing preferred embodiments of the invention, the same has been shown and now will be described in connection with its use as a part of a trouser creaser. With reference to Fig. 1, this device takes the form of an extensible frame, which is well known in the art. Here, two thin strips 11 and 12, of material such as steel, are formed, respectively, with top arms 13 and 14 and bottom arms 15 and 16. The arms of the creaser may be associated with each other in one of several ways, one of which will be described for the top arms of the device, only. As shown in Fig. 3, the arm 14 has fixed to its end a sleeve 17 in which the arm 13 is free to slide. Similarly, a sleeve 18 (Fig. 1) is attached to the end of the arm 13 in which sleeve the arm 14 is free to slide. With this arrangement of the

2

parts, the arms are held together closely and are free to move relative to each other. A clamp or locking device 19 is positioned with respect to each of the arms 13 and 14 to hold them against relative movement in selected positions. In a similar manner, the bottom arms 15 and 16 are held together by two sleeves 21 and 22 and are provided with a clamp or lock 23 which is identical with the clamp 19.

Thus, the trouser creaser is provided with top and bottom elements which are extendible to move the strips 11 and 12 in the leg of the trouser to stretch and crease the same. For this particular type of extensible frame, it is not required that the arms of the device be locked against outward movement. On the contrary it is desirable that they be free to move to extend the frame and that they be locked against inward or contracting movement, only, at any extended position, within the limit of their movement, to which they are urged. The clamps or locks 19 and 23 of the structure just described, which perform this required function and which form the subject matter of the instant invention, are identical and only one will be described in its preferred and modified forms.

Referring to the clamp 19, as viewed in Fig. 2, the same comprises a key 24 in which a slot 25 is made to receive the arm 13. The slot 25 is slightly larger than the arm 13 and the key 24 is thus free to rock on the arm 13 as indicated by the arrows in Figs. 3 and 4. The arm 14 is made with a bowed section 26 to which a key mounting member 27 is pivotally attached. The key mounting member 27 is formed from a flat strip of material and has a section 28 which lies substantially parallel with the arm 13. A second section 29 of the member 27 is normal to the arm 13 and has a slot 31 therein through which the said arm passes. A slot 32 in the section 28 also provides an opening through which the member 14 (particularly the bent section 26 thereof) passes. Further, the section 28 has another opening 33 therein through which a pin-like portion 34 of the key 24 is passed to pivotally connect the said key to the member 27, the key 24 being biased to its normal locking position (Fig. 3) by means of a coil spring 35 surrounding the member 13 and acting between the section 29 and the key 24.

With this arrangement of the parts the key 24 may be rocked about the arm 13 and due to the action of the spring 35, just described, the same is urged into its normal or locking position as illustrated in Fig. 3. In this position the

arms 13 and 14 are free to move outward, but the walls of the slot 25, being at an angle with the faces of the arm 13, present sharp edges which engage the latter and prevent inward relative movement of the arms.

When the key 24 is moved to the position it occupies in Fig. 4, the walls of the slot 25 are substantially parallel with the faces of the arm 13 and the latter is free to move in either direction in the key. To hold the key in its releasing position requires the continuous application of a force applied in the direction indicated by the arrows in Fig. 3. When this force is removed the spring 35 forces the key back to its normal locking position.

In one of its modifications, the locking device, illustrated in Figs. 2 to 4 takes the form illustrated in Fig. 5. Here, the distinguishing feature resides in a differently shaped key 36, the arms 13 and 14, the sleeve 17, the bowed section 26, the key mounting member 29 and the spring 35 being the same as shown in Figs. 2 to 4. The key 36 differs from the key 24 only in the fact that a thumb tab 37 is formed as a part thereof which lies substantially parallel to the arm 13. In this modification of the invention the releasing force of the key is applied essentially in the same manner as it is for the modification of the invention previously described. The addition of the thumb tab to the key, however, makes it easy to apply this force.

Various changes may be made in the details of construction, within the scope of the appended claims, without departing from the spirit of this invention. Parts of the invention may be used without the whole and improvements may be added while retaining some or all of the advantages of the invention.

What is claimed is:

1. In an extendible frame having two arms with means for holding the arms in substantially parallel abutting relationship with each other and slidably one with respect to the other, a clamp for locking the said arms against relative movement in one direction comprising a key having an opening therein through which a first of said arms is passed, said opening being dimensioned proportionately to the dimensions of said first arm but larger in area than the cross-sectional area of the first arm, a bowed section formed in the second of said arms, a key mounting member supported from said bowed section and having first and second sections parallel and normal,

respectively, to the first of said arms, said first section having a slot therein to receive said second arm and said second section having a slot therein to receive said first arm, means for pivotally connecting said key to said key mounting member, and a spring acting between said second section of said key mounting member and said key to bias the latter into a normal locking position.

- 5 10 15 20 25 30 35 40 45 50
2. A clamp for locking two slidable arms held together in substantially parallel abutting relationship one with the other, comprising a key having an opening therein through which a first of said arms is passed, said opening being dimensioned proportionately to the dimensions of said first arm but larger in area than the cross-sectional area of the first arm, a bowed section formed in the second of said arms, a key mounting member supported from said bowed section and having first and second sections parallel and normal, respectively, to the first of said arms, said first section having a slot therein to receive said second arm and said second section having a slot therein to receive said first arm, means for pivotally connecting said key to said key mounting member, and a spring acting between said second section of said key mounting member and said key to bias the latter into a normal locking position.
3. In an extendible frame having two arms with means for holding the arms in substantially parallel relationship with each other and slidably one with respect to the other, a clamp for locking the said arms against relative movement in one direction comprising a key having an opening therein through which a first of said arms is passed, said opening being dimensioned proportionately to the dimensions of said first arm but larger in area than the cross-sectional area of the first arm, a bowed section formed in the second of said arms, a key mounting member having separate slots therein through which is passed in one instance the first arm and in another instance the second arm, said first arm being slidably within its slot in the key mounting member, means for pivotally connecting said key to said key mounting member, and spring means operative against said key mounting member and said key to move the latter element into a normal locking position.
